(57) **CLAIM**

The ornamental design for a rollable display screen with sound bar as shown and described.

DESCRIPTION

1. Rollable display screen with sound bar

1.1 is a perspective view of a rollable display screen with sound bar, showing our new design;

1.2 is a front view thereof;

1.3 is a back view thereof;

1.4 is a left view thereof;

1.5 is a right view thereof;

1.6 is a top view thereof;

1.7 is a bottom view thereof;

1.8 is another front view of the rollable display screen with sound bar, shown in an alternate configuration;

1.9 is another front view of the rollable display screen with sound bar, shown in an alternate configuration;

1.10 is another front view of the rollable display screen with sound bar, shown in an alternate configuration; and

1.11 is another front view of the rollable display screen with sound bar, shown in an alternate configuration.

The present design is a rollable display screen coupled with a sound bar, which is rotatable, and usable in a perpendicular

(Continued)

version or a horizontal version; the broken lines indicate portions of the rollable display screen with sound bar that form no part of the claimed design; Reproduction 1.8 is a view showing that a display part is rolled completely; Reproduction 1.9 is a view showing that the present design is rotated, and used vertically; Reproduction 1.10 is a view showing that a display part is used vertically in the state of being rolled completely; Reproduction 1.11 is a view showing that the height of a display part is adjusted for use.
